UNITED STATES PATENT OFFICE.

SQUIRE AINSWORTH, OF PITTSBURG, PENNSYLVANIA.

IMPROVED WASHING-MACHINE.

Specification forming part of Letters Patent No. 98,902, dated January 18, 1870.

To all whom it may concern:

Be it known that I, SQUIRE AINSWORTH, of Pittsburg, in the county of Allegheny and State of Pennsylvania, have invented an Improved Washing-Machine; and I do hereby describe the same.

The object of my invention is the provision of a compact and simple washing-machine, adapted to effectively and expeditiously perform its work without injury to the clothes, to be easy of operation, and adapted to be readily cleansed.

My improved machine consists of an upright tub having a suitable corrugated or roughened internal surface, and a vertical rotary or oscillating rubber held down by a spring, and actuated, through suitable gearing, by a crank or lever, as preferred, all the working parts being attached to the lid of the tub and removable therewith.

The accompanying drawings, made a part of this specification, represent a crank-machine constructed according to my invention.

Figure 1 is a plan view; Fig. 2, a vertical section on the line $z z$, Fig. 1.

Similar letters of reference indicate like parts in the two figures.

A in the drawings may represent an upright tub, of suitable structure and material, and B a hinged cover, with which the same is provided.

A rotary rubber, consisting of a corrugated disk, C, provided with a perpendicular stem, D, is attached to the tub-cover B, and projects in the closed position of said cover, within the tub, said attachment being of such character as to permit of the vertical movement of the rubber, its stem passing through the cover. It may consist of a pin, d, traversing the rubber stem above the cover. The rotary or oscillating motion is imparted to the rubber C through a bevel-gear, E, through which its stem D passes, and it is held to its work by a spring, F, coiled around its stem and bearing against a shoulder thereon. A square or other non-circular opening in the gear E, embracing

a corresponding portion of the stem D, connects them.

The driving mechanism consists of a bevel-gear, G, mounted on a horizontal shaft, H, and actuated by a crank, I, or a lever. The shaft H is supported in brackets J, attached to the tub-cover B. An annular plate or ring, K, surrounding the central opening, provided in the tub-cover for the rubber stem D, forms a step for the gear E. A casting, L, of proper shape, forms an upper bearing for said gear and a cap to protect the same.

The spring F has its upper bearing on the gear E. Its lower bearing may be at the disk of the rubber a, (shown in Fig. 1,) in which case it may be secured by its end f being introduced through or under the stem, as represented.

The tub is preferably made of wooden staves and bottom, corrugated on their inner sides. It is also proposed to make it of corrugated sheet metal.

Operation: In use, the tub being supplied with water and the clothes to be washed placed in it, while the cover and its adjuncts are removed, the cover is closed, bringing the rubber down on the clothes. Motion is then imparted to the rubber by the crank or lever, while the rubber is held down with an elastic pressure by its spring.

The clothes, being kept constantly soaked with the water and pressed and rubbed between the rubber and the corrugated sides and bottom of the tub, are rapidly cleansed.

I claim as my invention—

The washing-machine herein described, consisting of a corrugated tub, A B, rotary rubber C, rubber stem D, spring F, gears E G, step K, cap and bearing L, shaft H, bearings J, and a crank, I, or a lever constructed, combined, and arranged as set forth, for the purposes shown.

SQUIRE AINSWORTH.
